KNITTING MACHINE

Vincent Lombardi, Garden City, N. Y., assignor
to Lombardi Knitting Machine Co. Inc., New
York, N. Y., a corporation of New York

Application January 30, 1936, Serial No. 61,516

27 Claims. (Cl. 66—50)

This invention relates to knitting machines.

An object of the invention is the provision of an accurate, readily operated machine whereby design fabrics may be produced in a simple and effective manner.

Another object of the invention is to provide a simply constructed, readily operated machine whereby a wide variability in pattern formation may be had.

10 Another object is the provision of a control element for knitting machines of such character that an accurate and certain adjustment thereof may be readily effectuated.

Other objects of the invention will in part be 15 obvious and will in part appear hereinafter.

The invention accordingly comprises the features of construction, combinations of elements, and arrangement of parts, which will be exemplified in the constructions hereinafter set forth 20 and the scope of the application of which will be indicated in the claims.

For a fuller understanding of the nature and objects of the invention reference should be had to the following detailed description taken in connection with the accompanying drawings, in 25 which:

Figure 1 is a plan view of a portion of a machine embodying the invention;

Fig. 2 is a vertical sectional view along the 30 line 2—2 in Fig. 1;

Fig. 3 is a partial vertical sectional view along the line 3—3 of Fig. 1;

Fig. 4 is a partial perspective view of one of the pattern wheel portions shown in Fig. 3;

Fig. 5 is a horizontal sectional view along the 35 line 5—5 of Fig. 2;

Fig. 6 is a side view of a cam element shown in Fig. 5;

Fig. 7 is an end view on a reduced scale of a 40 portion of the mechanism at the lower left hand side of the machine as viewed in Fig. 2;

Fig. 8 is a perspective view of one of the inserts of Fig. 7;

Fig. 9 is a vertical sectional view of a modified form of rotatable pattern means;

Fig. 10 is a partial sectional view along the lines 10—10 of Fig. 9; and

Fig. 11 is a perspective view of one of the inserts shown in Figs. 9 and 10.

50 Pattern wheels have long been used for the setting of various elements in a needle bed and pattern drums have likewise been used for such purpose. Similarly, various types of rotary pattern elements having actuating portions at different levels have been used to actuate needles,

jacks, etc., the actuation taking place at the various levels depending upon the character of the needle or jack, or other element. However, it is widely recognized that pattern wheels are distinctly limited in the designs which they can produce, and that the change from one pattern wheel to another requires the stopping of the machine, with consequent delays in production, necessity for continuous attention, and danger that the yarns or certain of the parts will accidentally be moved out of position during the replacement operation. Drum machines, whether of the single-level or multiple-level type, are exceedingly complicated, cumbersome and expensive, and the use of multiple-level drums requires a particular arrangement of the elements upon which the drum operates, and involves a definite limitation on the pattern formation.

With the foregoing and other considerations in view, the present invention contemplates the provision of a machine embodying a rotary pattern unit wherein there are provided a plurality of rows of selective means, and embodying means for bringing one or another of said rows into operative position. The rows of selective means may be in the form of pattern wheels, in the form of rows of elements removably or otherwise disposed on the rotary unit, or in other suitable form.

In my co-pending applications, Serial No. 680,- 30 168, filed July 13, 1933, and Serial No. 720,921, filed April 17, 1934, there are disclosed actuatable elements for knitting needles and the like which are in the form of rockers adapted to be set in one of a multiplicity of lateral positions by a pattern wheel or the like and to be selected and moved by a cam depending upon which of said positions they are in. Various means for holding such rockers in their said positions are disclosed in the above noted and other of my co-pending applications and these have operated effectively for many purposes. However, in many types of machines the maximum of precision of operation is highly desirable, and in all machines any increase in accuracy, results in a more satisfactory machine. With the foregoing in view, the invention in certain of its aspects contemplates the provision of a control element which will be retained in a set position with such certainty that an exceedingly high degree of assurance of accuracy in operation may be had.

While a particular form of machine is exemplified herein, it will be appreciated that the elements operated upon may be of any desired type; that the bed on which they are carried may 55

be stationary or movable, and may be of any desired form or shape.

In the form of construction exemplified, there is provided a bed 5 which, in the present instance, is in the form of a stationary cylinder formed with slots 6 in which needles 7 are slidably mounted. Beneath each needle there is provided a selective element 8 mounted for swinging movement and also for sliding movement in the slot. In accordance with the invention disclosed and broadly claimed in my said application, Serial No. 680,168, the lower portion of the selective element or rocker 8 is formed with a plurality of cam-engaging surfaces in the form of shoulders 9 and 10 adapted to be selectively engaged by a cam 11 carried by a revolving support 12; the shoulders 9 and 10 being so disposed that when the lower portion of the rocker is entirely within the slot 6, neither shoulder will be engaged by the cam, but that when the shoulder 9 protrudes from the slot, it will be engaged by the cam 11 and the rocker and needle advanced a predetermined distance, and so that when the shoulder 10 protrudes from the slot, this shoulder will be engaged by the cam 11 and the rocker and needle advanced a greater distance. Movable with the support 12 are a suitable number of yarn feeds of any well known or suitable type, and actuator mechanism, including a like number of cams 11 and of other elements hereinafter to be exemplified.

In the present instance, each rocker is formed with a forked upper portion including outwardly resilient prongs 13 and 14. The support 12 carries an annular member 15 adapted to bear against the prong 13, so as to compress the prongs slightly between the annular member and the bed and to provide a resilient grip which will tend to hold the rocker accurately in the position in which it has been set. As will be observed, the prongs 13 and 14 are provided with curved surfaces 16 and 17 respectively, to facilitate the pivotal movement of the member whereby the lower portion is set in the desired position for proper operation of the cam 11, and the annular member 15 is formed with a curved-base recess 18 of such nature that the surface 16 will readily swing therein. As will be apparent from Fig. 5, the member 15 is cut away at 19 above the recess 18 and even therewith at those portions where the cams operate, so that the member will hold the rocker in the slot during the cam operation, but will permit ready longitudinal movement thereof. Each of the rockers is provided with a depending butt 20 having an inner edge 21 adapted to be engaged by any of a suitable number of cams 21', so as to swing the lower portion of the rocker laterally into a fully swung outward position wherein the shoulder 10 may be engaged by the cam 11. Each rocker is likewise provided with an actuable portion 22 whereby the lower end of the rocker may be pressed inwardly part way, or all the way, as desired, so as to move the shoulder 10, or both of the shoulders 9 and 10, out of cam-engaging position.

In order to effectuate the inward swinging movements of the rockers, there are provided a suitable number of rotatable pattern means in the form of pattern units 24 each comprising a plurality of pattern wheel portions 25, each serving to provide a row of selective means adapted to act selectively upon the actuable portions 22 of the rockers 8. Each pattern wheel 25 in the present instance, is selectively formed to provide

long actuator portions 26 at certain positions thereon, short actuator portions 27 at other positions, and no actuator portions at still other positions indicated at 28; so that, where a long actuator portion contacts with the actuable portion 22 of a rocker, the rocker will be swung entirely within the slot 6 so as to permit the cam 11 to pass the rocker without moving it; where a short actuator portion 27 contacts with the portion 22, the rocker will be swung enough to move the shoulder 10 within the slot 6 so as to permit the shoulder 9 to be engaged by the cam 11; and where no actuator portion is on the pattern wheel where it comes into proximity to the portion 22, the rocker will be left in the position in which it was placed by the cam 21' and the shoulder 10 will be engaged by the cam 11.

The pattern wheel unit comprises a central post 29 on which there are carried the various pattern wheels 25, upper and lower plates 30 and 30a, a collar 31, a plate 31a, and a gear 32. The wheels 25 and plates 30 and 30a are aligned by means of a pin 33, and the various rotatable portions are clamped together by nuts 34 threaded on the post 29. The gear 32 meshes with a gear 35 on the bed 5. In order to assure that each actuator portion 26 or 27 will exactly meet an actuable portion 22, there is provided adjustable means comprising screws 36 extending thru posts 37 carried by the plate 30a and bearing against posts 38 extending from the plate 31a. By turning the screws 36, the unit 24 may be swung in one direction or the other to move the actuator portions on the wheels exactly to a position where the actuator elements will meet the actuable elements squarely and without tendency to bend or break the same.

In accordance with the present invention, the post 29 is vertically adjustable so that any desired one of the wheels 25 may be brought into the position occupied in the figure by the lowermost wheel wherein the desired wheel will selectively actuate the aligned actuable portions 22 of the rockers 8. To this end, the lower end of the post 29 is in tubular form, as indicated at 39, to receive an upright bearing post 40, carried by the support 12, and the post 29 is slidably mounted in a bearing 41 carried by a removable casing 45 which forms a part of the support 12 and serves to enclose the wheels and the gearing. In order that the post may be slid in its bearings to bring any desired one of the wheels 26 into operative position, there is provided adjusting means comprising a bracket 46 having arms 47 carrying rounded portions 48 fitting between plates 49 on a head 50 which is threaded on the upper end of the post 29, so that a swinging movement of the bracket on a pivot 51 will cause the post 29 to be raised or lowered. At the other side of the pivot from the arms 47 the bracket is formed with an arm 52 having a surface 53 so inclined that a pressing movement of a given extent at different points along this surface will impart to the bracket when it is not otherwise held such movement as will bring one or another of the wheels 26 into operative position. Normally the bracket is held in adjusted position by means of a catch 54 fitting into one or another of the notches of a ratchet 55 carried on the lower end of the arm 52; a spring 56 being provided to hold the bracket against the catch. The position of the bracket 46 and of the post 29 having been adjusted, as by means hereinafter to be described, so as to bring one or another of the wheels 25 in line with the portions 22, the

machine will operate with the actuators 26 and 27 on the operative pattern wheel serving to selectively thrust inwardly those rockers which have been swung out by the cam 21, whereupon 5 the cam 11 will selectively act on the rockers, depending on their setting, to advance the rockers and the needles, the cam 11 operating after the portion 15 has passed beyond the rockers. After the needles have selectively taken a yarn 10 from a yarn feed in any well known or suitable manner, those needles which have been advanced may be retracted, as by a stitch cam 51. Ordinarily a pattern wheel unit with its associated axis is provided at each yarn feed.

15 In order to operate the bracket 46 in a pre-determined manner to impart a desired succession of designs to a fabric being formed, there is provided control means 58 which is immovable with respect to the needle bed, being stationary 20 when the bed is stationary as in the exemplified construction, so as to be operative once in every revolution of the actuating mechanism. Any desired number of such control means may, of course, be provided. The exemplified control 25 means comprises a control cam plate 60, carried by a plate 61 supported on posts 62 which are mounted for vertical sliding movement in a frame 63, to permit the cam plate 60 to be raised to one or another of positions a, b, c, and d indicated 30 in Fig. 2, such that a bracket 46 will contact therewith at various points along the surface 53. Between the lower ends of the posts 62 there extends a cross piece 64 carrying a downward projection 65. One arm 66 of a lever member 35 pivoted at 67 bears against the lower portion of the projection and the other arm 68 of this lever is in the form of a trip member and extends alongside of a shift wheel 69 having generally radial slots 70 in its periphery. Selectively disposed 40 in these slots to provide the desired control for the pattern are a plurality of inserts 71 which are formed (Fig. 8) with lateral grooves 72 to engage the edges of the slot and with projections of various extents radial of the wheel, as indicated at 73a (Fig. 8) and 73b, 73c, and 73d (Fig. 7). The wheel 69 is rotated periodically by any suitable means, such as a pattern chain, so as to bring one slot after another past the arm 68. When a slot without an insert 71 moves 45 past the arm 68, the posts 62 and plate 61 will not be moved upwardly. When a slot with an insert 73a moves past the arm 68, the posts will be raised to move the cam plate 60 to the position a in Fig. 2. When a slot with an insert 50 73b moves past the arm 68, the posts will be raised to move the cam plate 60 to the position b in Fig. 2. When a slot with an insert 73c moves past the arm 68, the posts will be raised to move the cam plate 60 to the position c in Fig. 2. When a slot with an insert 73d moves past the arm 68, the posts will be raised to move the cam plate 60 to the position d in Fig. 2. The inserts are held in the wheel 69 by means of screws 74 extending into openings 75 in the wheel. 55

55 In order to release the catch to permit the bracket 46 to be moved by the spring 56 to such position as is permitted by the positioning of the cam member 60, there is provided a cam 79 on horizontally slideable posts 80. When the cam is 60 projected toward the bed it serves, as a member 81 passes the cam 79, to press downwardly the member 81, the member 81 is connected with the catch 54, and in order that the catch 54 may be accurately adjusted, so that it will hold the 65 bracket 46 in such position that the opera-

tive wheel 25 will be accurately disposed, the connection between the member 81 and the catch 54 is of an adjustable nature and comprises a screw 82 threaded thru the member 81 and bearing against the catch 54 and a screw 83 threaded 70 thru the member 81 and extending thru an opening 84 in the catch 54. The member 81 is supported by an arm 85 pivoted at 86 and having fastened thereto one end of a spring 87 which serves to hold the catch 54 normally in one of 75 the notches at the lower end of the bracket 46. Accordingly when the member 81 passes the cam 79 when the latter is in an inwardly projecting position, the cam 79 will press the member 81 downwardly against the pull of the spring 87 and will remove the catch 54 from its notch, allowing the spring 56 to pull the bracket 46 against the member 60 if the latter has been moved to a lower position. If, on the other hand, the member 60 is moved to a higher position, as for instance, from the position b to the position d, it will bear against the surface 53 on the bracket during the passage thereof, and because of the ratchet construction at 55 will cause the catch 54 to move to a notch which is further from the 25 needle bed, the spring 87 permitting such slipping movement of the catch.

The cam 79 and posts 80 are held in an outward position when the posts 62 are in a downward position, by means of cam members 88 30 depending from the plate 61 and bearing against a cross piece 89 on the posts 80. Upon the upward movement of the posts 62 by any of the projections 73a, 73b, 73c, and 73d, however, the cam members 88 are removed from their position 35 against the cross piece and the cross piece and the posts 80 are slid inwardly by a spring 89' to move the cam 79 in the path of the member 81. 40

As will be understood, the invention in its broader aspects contemplates the provision of a wide variety of forms of rotary pattern units. By way of example, there is illustrated in Figs. 9 and 10 a form of construction wherein the pattern unit comprises a hub portion 90 formed with notches 91 in its periphery, and also upper and lower plates 92 and 93 connected by axial members 94 providing therebetween slots 94a which are aligned with the notches 91. In each slot there are selectively disposed inserts 95 such as shown in Fig. 11. Each insert is formed with a head, the heads on various ones of the inserts being of different extent in the present instance, as indicated at 96a and 96b, and inserts are omitted from certain of the slots 94a, so that a three-effect row of selective means may be provided. In the present instance there are provided four such rows, as indicated at A, B, C, and D which are adapted to be placed in operative position by the disposal of the cam member 60 in one or another of the positions a, b, c, and d, respectively. The rows of inserts are separated by spacer plates 97, and these plates, together with the upper and lower plates 92 and 93, are formed with holes thru which pins 98 are adapted to be thrust; each insert being formed at each edge with a notch 99 adapted to receive the pins 50 to hold the inserts firmly in position. 55

It will thus be seen that there are provided a plurality of rows of selective means each adapted to be brought into a position to selectively operate aligned actuatable portions with ease and effectiveness, and also selective elements of an improved type; by means of which design fabrics may be produced in a highly satisfactory manner. 60

Since certain changes may be made in the above 65

construction and different embodiments of the invention could be made without departing from the scope thereof, it is intended that all matter contained in the above description or shown in the accompanying drawings shall be interpreted as illustrative and not in a limiting sense.

I claim:

1. In a circular knitting machine comprising a bed and actuator mechanism, said actuator mechanism and said bed being mounted for relative rotation on an axis extending thru the center of said bed, a series of settable elements carried by said bed and having actuatable portions adapted to be aligned, and pattern means constituting a part of said actuator mechanism and rotatable on its axis in response to said relative rotation and formed to provide a plurality of rows of selective means each adapted when brought into a given position to selectively and directly actuate the aligned actuatable portions, said rotatable pattern means being movably mounted to permit one or another of said rows of selective means to be brought into said position as desired.
2. In a knitting machine comprising a knitting bed and actuator mechanism, said actuator mechanism and said bed being mounted for relative movement, a series of settable elements carried by said bed and having actuatable portions adapted to be aligned, pattern means constituting a part of said actuator mechanism and rotatable in response to said relative movement and formed to provide a plurality of rows of selective means each adapted when brought into a given position to selectively and directly actuate the aligned actuatable portions, and means to bring one or another of said rows of selective means into said position as desired.
3. In a knitting machine comprising a knitting bed and actuator mechanism, said actuator mechanism and said bed being mounted for relative movement, a series of settable elements carried by said bed and having actuatable portions adapted to be aligned, pattern means constituting a part of said actuator mechanism and rotatable in response to said relative movement and formed to provide a plurality of rows of selective means each adapted when brought into a given position to selectively and directly actuate the aligned actuatable portions, and pattern controlled means for bringing various ones of said rows of selective means into said position from time to time during the operation of said machine.
4. In a knitting machine comprising a bed and actuator mechanism, said actuator mechanism and said bed being mounted for relative movement, a series of settable elements carried by said bed and having actuatable portions adapted to be aligned, and a pattern member constituting part of said actuator mechanism and rotatable in response to said relative movement and including means providing a plurality of rows of selective means, each adapted when brought into a given position to selectively and directly actuate the aligned actuatable portions, said rotatable pattern member being movably mounted to permit one or another of said rows of selective means to be brought into said position as desired, and said row-providing means being formed to permit the alteration of the character of the selective means in any individual ones of said rows.
5. In a knitting machine comprising a bed and actuator mechanism, said actuator mechanism and said bed being mounted for a relative movement, a series of settable elements carried by said bed and having actuatable portions adapted to be

aligned, a rotatable pattern member constituting part of said actuator mechanism and including means providing a plurality of rows of selective means, each adapted when brought into a given position to selectively actuate the aligned actuatable portions, said rotatable pattern member being movably mounted to permit one or another of said rows of selective means to be brought into said position as desired, said row-providing means comprising a plurality of pattern wheels each providing a multiplicity of selectively disposed actuator portions, and means to mount said wheels to permit them to be removed and replaced.

6. In a knitting machine comprising a bed and actuator mechanism, said actuator mechanism and said bed being mounted for relative movement, a series of settable elements carried by said bed and having actuatable portions adapted to be aligned, a pattern member constituting part of said actuator mechanism and rotatable in response to said relative movement and including means providing a plurality of rows of selective means, each adapted when brought into a given position to selectively and directly actuate the aligned actuatable portions, said rotatable pattern member being movably mounted to permit one or another of said rows of selective means to be brought into said position as desired, said row-providing means comprising a plurality of individually removable and replaceable inserts in each row, and means common to said rows to retain said inserts.

7. In a knitting machine comprising a bed and actuator mechanism, said actuator mechanism and said bed being mounted for relative movement, a series of settable elements adjustably carried by said bed and having actuatable portions adapted to be aligned, and pattern means constituting a part of said actuator mechanism and rotatable in response to said relative movement and formed to provide a multiplicity of rows of selective means each adapted when brought into a given position to selectively bear against the aligned actuatable portions in a direction transverse to said bed and to set the same by a movement in said direction, said rotatable pattern means being movably mounted to permit one or another of said rows of selective means to be brought into said position as desired, and said actuatable portions projecting outwardly from said settable elements in a direction away from said bed, so that only one of said rows will be aligned therewith at a given time.

8. In a knitting machine comprising a bed and actuator mechanism, said bed and said actuator mechanism being mounted for relative movement, a series of similar needle jacks carried by said bed, pattern means constituting a part of said actuator mechanism and rotatable in response to said relative movement, said rotatable pattern means being formed to provide a plurality of rows of selective means each adapted for the selective and direct actuation of said needle jacks when in a given position, and means to bring various ones of said rows of selective means into said position at various times in the operation of said machine.

9. In a knitting machine comprising a bed and actuator mechanism, said bed and said actuator mechanism being mounted for relative movement, a series of similar actuatable elements carried by said bed, rotatable pattern means constituting a part of said actuator mechanism, said rotatable pattern means being formed to provide

a plurality of rows of selective means each adapted for the selective actuation of said actuatable elements when in a given position, means to bring various ones of said rows of selective means into said position at various times in the operation of said machine, said positioning means comprising a control member having a single control element and carried on a support which is immovable with respect to said bed, said control member being movable between a plurality of positions, an adjustable member associated with said actuator mechanism and adapted to contact said control element when the control element is at least in a plurality of said positions and to be movable differently depending on which of the latter positions the control element is in so as to be adjusted from time to time during the operation of said machine in accordance with the variation in position of the control element, means to vary the position of said control element, means to bring various ones of said rows of selective means into said given position in accordance with the position of said adjustable member, and means to hold said adjustable member in an adjusted position.

10. In a knitting machine comprising a bed and actuator mechanism, said actuator mechanism and said bed being mounted for relative movement, a series of settable elements carried by said bed and having actuatable portions adapted to be aligned, pattern means constituting part of said actuator mechanism and rotatable in response to said relative movement and formed to provide a plurality of rows of actuator portions selectively disposed at desired ones of evenly spaced points about the periphery of each row, and means to adjust the circumferential position of said points so that said actuating portions will actuate said actuatable portions, each of said rows being adapted when brought into a given position to selectively and directly actuate the aligned actuatable portions, and said rotatable pattern means being movably mounted to permit one or another of said rows to be brought into said position as desired.

11. In a knitting machine comprising a bed and actuator mechanism, said actuator mechanism and said bed being mounted for relative movement, a series of settable elements movably carried by said bed and having actuatable portions adapted to be aligned, rotatable pattern means constituting a part of said actuator mechanism and formed to provide a plurality of rows of selective means each adapted when brought into a given position to selectively actuate the aligned actuatable portions, said rotatable pattern means being movably mounted to permit one or another of said rows of selective means to be brought into said position as desired, said settable elements being formed with a forked portion having compressible means, and means to compress said compressible means to frictionally resist movement of said settable elements but to permit movement to be imparted thereto, said rotatable pattern means being adapted to selectively impart a setting to said settable elements while the compressible means thereof is compressed by said compressing means.

12. In a knitting machine comprising a bed and actuator mechanism, said actuator mechanism and said bed being mounted for relative movement, a series of settable elements swingably carried by said bed and having actuatable portions adapted to be aligned, and rotatable pattern means constituting a part of said actu-

ator mechanism and formed to provide a plurality of rows of selective means each adapted when brought into a given position to selectively actuate the aligned actuatable portions, said rotatable pattern means being movably mounted to permit one or another of said rows of selective means to be brought into said position as desired, said settable elements being formed with a forked portion having resiliently compressible prongs with edge surfaces at least one of which is curved, and said machine being provided with means to engage said edge surfaces and to compress said forked portions slightly to frictionally resist movement of said settable elements to assure an accurate setting.

13. In a circular knitting machine, in combination, actuator mechanism, a needle cylinder, a series of slots in said cylinder, settable elements in said slots and having actuatable portions adapted to protrude therefrom and to be aligned, rotatable pattern means constituting a part of said actuator mechanism, said rotatable pattern means and said cylinder being mounted for relative movement in a direction generally at right angles to said slots, said rotatable pattern means being formed to provide a plurality of rows of selective means each adapted when brought into a given position to selectively and directly actuate the aligned actuatable portions, and means to bring one or another of said rows into said position as desired.

14. In a knitting machine comprising a bed and actuator mechanism, said actuator mechanism and said bed being mounted for relative movement, a series of settable elements carried by said bed and having actuatable portions adapted to protrude outwardly therefrom and to be aligned, rotatable pattern means constituting a part of said actuator mechanism and adapted to selectively actuate the aligned actuatable portions, said actuatable portions carrying projections having inner edges facing toward said bed and adapted to be engaged by a setting cam for imparting lateral movement to the settable elements, and a setting cam forming a part of said actuator mechanism and arranged to extend between said inner edges and said bed to position said actuatable portions for engagement thereof by said rotatable pattern means.

15. In a knitting machine, a bed and actuator mechanism, said actuator mechanism and said bed being mounted for relative movement, a series of settable elements carried by said bed and formed with hook-like portions, rotatable pattern means constituting a part of said actuator mechanism and formed to provide a plurality of rows of selective means each adapted when brought into a given position to selectively actuate aligned actuatable surfaces of the settable elements, said rotatable pattern means being movably mounted to permit one or another of said rows of selective means to be brought into said position as desired, said settable elements being formed with a forked portion having resiliently compressible prongs with edge surfaces at least one of which is curved, and said machine being provided with means to engage said edge surfaces and to compress said forked portions slightly to frictionally resist movement of said settable elements to assure an accurate setting.

thereof, each hook-like portion having an outer surface adapted to be engaged by selective means in said given position to swing a settable element in one direction on the forked portion and 5 having an inner edge which is adapted to be engaged by a cam to swing the settable element in another direction on said curved surfaces, and a cam forming a part of said actuator mechanism for engaging the inner edges of said hook-like portions.

16. A selective element for a knitting machine comprising a forked end portion having resiliently compressible means adapt'd to engage opposing portions of a machine in a manner which 15 will permit the element to be swung on its forked end, but which will offer frictional resistance to movement of the element during a setting operation to assure an accurate setting thereof, and comprising also a projection including a portion 20 extending laterally of the element and a portion extending from the aforesaid portion longitudinally of the element and having an inner surface disposed oppositely to a longitudinal edge surface of the element and adapted to be engaged by a setting cam disposed between said inner surface and said edge surface.

17. A selective element for a knitting machine comprising a forked portion having prongs which are outwardly resilient in the direction of the 30 width of the element and formed with at least one curved surface, and a hook-like portion, the outer surface of which is adapted to be engaged by pattern means to swing the element in one direction on the forked portion and the inner 35 edge of which is adapted to be engaged by a cam to swing the element in another direction on the forked portion.

18. In a knitting machine, knitting element means comprising a base member having a laterally extending hook-like portion including a portion extending longitudinally of the base member, a surface on the outside of said hook-like portion for engagement with means to move said base member in one direction and a surface on the inside of said longitudinally-extending portion for engagement with means to move said base member in another direction.

19. In a knitting machine comprising a bed and actuator mechanism, said actuator mechanism and said bed being mounted for relative movement, a series of settable elements carried by said bed and having a body and actuatable portions adapted to protrude therefrom and to be aligned, rotatable pattern means constituting a part of said actuator mechanism and adapted to 50 selectively actuate the aligned actuatable portions, said actuatable portions carrying projections having inner edges extending in opposed relation to the body of the settable elements and adapted to be engaged by an aligning cam, and an aligning cam adapted to engage said inner edges to 55 position said actuatable portions for engagement thereof by said rotatable pattern means.

20. In a knitting machine a bed and actuator mechanism, said actuator mechanism and said bed being mounted for relative movement, a series of settable elements carried by said bed and formed with hook-like portions, selective means constituting part of said actuator mechanism, each hook-like portion having an outer surface adapted to be engaged by said selective means to move said settable elements laterally in one direction and having an inner edge which is adapted to be engaged by a cam to move the 70 settable element laterally in another direction.

and a cam forming a part of said actuator mechanism for engaging the inner edges of said hook-like portions.

21. A selective element for a knitting machine comprising a forked portion having resiliently compressible means for engaging opposed portions of a machine to resist movement of the element during a setting operation to assure an accurate setting thereof, and comprising also a projection having an inner surface adapted to 10 be engaged by a setting cam, said inner surface extending in opposed relation to the body of said element.

22. In a knitting machine, a bed and actuator mechanism, said actuator mechanism and said bed being mounted for relative movement, a series of settable elements carried by said bed and provided with forked portions, each of said forked portions comprising resiliently compressible means, means for compressibly retaining said forked portions, said retaining means and said forked portions being formed to permit said settable elements to be swung on a pivot at said forked portions, and means forming part of said actuator means to swing said settable elements 25 on their forked portions.

23. In a knitting machine, a bed and actuator mechanism, said actuator mechanism and said bed being mounted for relative movement, a series of settable elements carried by said bed and provided with forked portions, each of said forked portions comprising resiliently compressible means, means for compressibly retaining said forked portions, said retaining means including a portion associated with said actuator means, 35 and said retaining means and said forked portions being formed to permit said settable elements to be swung on said forked portions, means forming part of said actuator means to set at least certain of said settable elements by imparting thereto swinging movement on their forked portions, and means forming part of said actuator mechanism for imparting longitudinal movement to at least certain of said settable elements at a given point in said relative movement, said portions and said retaining means being formed to resist longitudinal movement of said settable elements during the operation of said setting means, but to permit longitudinal movement of said settable elements during the operation of the means for imparting longitudinal movement thereto.

24. A selective element for a knitting machine comprising two portions spaced longitudinally of the element, one of said portions having a cam-engaging shoulder and the other of said portions being forked and having resiliently compressible means adapted to be engaged by opposing portions of a machine in a manner which will offer frictional resistance to the movement of the element but which will permit the element to be 55 swung to set the same.

25. In a knitting machine comprising a bed and actuator mechanism, said actuator mechanism and said bed being mounted for relative movement; a series of settable elements each formed with a forked portion having compressible means, means to compress said compressible means during at least a part of said relative movement so as to frictionally resist movement of the settable elements, and selective means operative on said settable elements during the operation of said compressing means to move selected ones of said settable elements to a set position in spite of said frictional resistance and to leave others of said settable elements in place, the compressing means 70 75

being arranged to maintain said frictional resistance to retain said settable elements in the positions in which they are left by said selective means.

5 26. In a knitting machine comprising a bed and actuator mechanism, said actuator mechanism and said bed being mounted for relative movement; a series of settable elements each formed with a forked portion having compressible means,
10 means to compress said compressible means during at least a part of said relative movement so as to frictionally resist movement of the settable elements, means operative during the operation of said compressing means to position said settable elements for a setting operation, said positioning means being operative to move said settable elements in spite of said frictional resistance, selecting means operable upon the settable elements, said frictional resistance of said compressing
15 means serving to retain the elements in position for action by said selective means.

27. In a knitting machine comprising a bed and actuator mechanism, said actuator mechanism and said bed being mounted for relative movement; a series of settable elements each formed with a forked portion having compressible means, means to compress said compressible means during at least a part of said relative movement so as to frictionally resist movement of the settable elements, means operative during the operation of said compressing means to position said settable elements for a setting operation, and selective means operable on the positioned settable elements during the continued operation of said compressing means to move certain of said settable elements to a set position and to leave others of said settable elements in place, the compressing means being arranged to maintain said frictional resistance thruout the operation of said positioning means and said setting means. 5
